CLAIM

The ornamental design for a paper product, as shown and described.

DESCRIPTION

FIG. 1 is a top plan view of a paper product showing our new ornamental design; and,

FIG. 2 is an enlarged sectional view of the paper product of FIG. 1 taken along line 2—2.

The inner perimeter of dash/dot lines defines the repeat unit of the paper product, which repeats uniformly throughout the entire surface of the paper product. The outer perimeter of broken lines indicates that a specific length and width of paper product form no part of the claimed design. The broken line showings are for illustrative purposes only and also form no part of the claimed design. The surfaces or portions not shown in the drawings or described in the specification form no part of the claimed design.
